(57) **CLAIM**

The ornamental design for adaptor for extending the length
of trailer tongues, as shown and described.

DESCRIPTION

FIG. 1 is a side view of the adaptor for extending the length
of trailer tongues, showing my new design;

FIG. 2 is a top view thereof;

FIG. 3 is an opposite side view thereof;

FIG. 4 is a bottom view thereof;

FIG. 5 is an end view thereof; and,

FIG. 6 is an opposite end view thereof.
